UNDERGARMENT

Frank N. Mason, Charleroi, Pa., assignor of one-fourth to Robert C. Mason, Pittsburgh, Pa.

Application September 3, 1947, Serial No. 771,949

6 Claims. (Cl. 2-224)

1

This invention relates to an improved undergarment, and more particularly to an undergarment adapted to extend just below the wearer's knees.

The usual type of men's undergarment terminates a short distance below the wearer's crotch. It permits the knees and a large part of the thighs to come into tight contact with the trousers when the knees are bent, as in sitting or squatting. This condition has numerous disadvantages. If the trousers are made of rough or coarse material, they tend to irritate the skin, particularly in warm humid weather when the skin is damp with perspiration, at which time they also may stick to the skin. Further, perspiration is absorbed by the trousers, frequently discoloring them, obliterating their pressed creases, and contaminating them with a disagreeable odor. Accordingly, trousers must be frequently cleaned; and dry cleaning is expensive. To avoid some of these disadvantages, the more expensive trousers are generally provided with a lining which is attached to the front portion of each trouser leg and extends a short distance above and below the knee; but such linings are not available on most trousers, they are not readily removable for washing, and they tend to ameliorate rather than eliminate the disadvantages referred to.

The foregoing disadvantages, however, can be largely or entirely eliminated if the undergarment extends below the wearer's knees, since the undergarment acts as an absorbent lining for the trousers and is separately laundered. While this fact has long been recognized, such undergarments have not been widely accepted, because, among other things, the legs of the undergarment tend to creep upward and to be twisted about the wearer's legs, resulting in binding and discomfort. While such undergarments have been provided with means for preventing this upward creep and twisting, those means either exert a continuous downward pull on the undergarment which is uncomfortable, or they bind the knees of the wearer when the knees are bent.

An object of this invention is to provide an improved form of undergarment, at least the lower portion of which is made of relatively inelastic material, and which is adapted to extend below the knees of the wearer and to be there held in place without exerting a downward pull upon the undergarment to discomfort the wearer and without binding when his knees are bent.

Another object is to provide such an undergarment that may be easily and cheaply manufactured and that is convenient to use.

A further object is to provide such an undergarment that is adapted to act as a sock supporter.

In accordance with this invention a one-piece undergarment, or the lower part of a two-

2

piece undergarment, has leg portions which are adapted to reach just below the wearer's knees. The leg portions have a considerably larger circumference than the human leg, so that they will loosely cover the legs. The lower extremity of each leg portion is provided with a hem or band, made of relatively inelastic material, which likewise is of considerably greater circumference than the adjacent circumference of the human leg just below the knee. Within the circumference of the hem is disposed a relatively short elastic tape having its ends detachably secured to the sides of the hem. The tape is adapted to rest directly against and to extend around the front portion of the wearer's leg just below the knee and to draw the back and side portions of the hem against the back and sides of the leg. The garter-like combination of tape and hem will prevent twisting and creeping of the undergarment without exerting a downward pull thereon. The front part of the hem and the undergarment material above it will be loosely disposed in front of the wearer's knee, which will effectively prevent binding of the undergarment when the knee is bent. The elastic tape may be provided with depending catches to engage and support a sock on the wearer's leg.

The preferred embodiment of this invention is illustrated in the accompanying drawings, of which Fig. 1 is a front elevation of the leg portion of an undergarment made in accordance with this invention, as it would appear on a human leg; Fig. 2 is a side elevation of the same; and Fig. 3 is a horizontal section along line III-III in Fig. 1.

Referring to the drawings, a one-piece undergarment, or the drawers of a two-piece undergarment, of otherwise conventional shape has a leg portion 1 adapted to extend just below the wearer's knee. The leg portion has a band or hem 2 at its bottom, and at least the hem, and preferably the entire garment, is made of relatively inelastic material that will fit the wearer's leg 3 very loosely. An elastic tape 4 of any suitable material is disposed within the circumference of the hem and has its ends detachably secured to the sides of the hem by some suitable means, such as buttons 5 on the tape engaging buttonholes 6 in the sides of the hem. The elastic tape is preferably long enough to extend around only a small portion of the wearer's leg and is adapted to rest directly against the front of the leg and to draw the back and sides of the hem 2 against the back and sides of the leg as shown in Fig. 3. As a result, the hem and the elastic tape together form a snug garter around the leg, just below the knee and above the outward swelling of the calf muscles. Minor variations in the circumference of the human leg at this point are accommodated by the elastic tape, and substantial

variations in leg sizes may be readily accommodated by providing additional buttonholes 7 in the hem behind holes 6 to adjust the size of the garter formed by the tape and hem. Both the tape and hem are of sufficient width to prevent any uncomfortable localized pressure on the wearer's leg.

It is a feature of this invention that when the tape is buttoned in place the front portion of the hem in the undergarment and the undergarment material above it are loosely disposed in front of the wearer's knee, as shown in Figs. 2 and 3, which will prevent any binding of the undergarment when the knee is bent. It is a further feature of this invention that while the leg portion of the undergarment is effectively prevented from twisting or creeping upward on the wearer's leg because it is held securely just below the knee, there is no sustained downward pull upon the undergarment to discomfort the wearer.

Depending from the elastic tape 4 are one or more, preferably two, catches 8 adapted to engage a sock 9 on the wearer's leg. Since the sock is supported by the garter-like combination of the hem and elastic tape, and that combination snugly encircles the leg above the calf, the sock will not exert any appreciable downward tension on the undergarment.

It will be readily appreciated that undergarments made in accordance with this invention may be easily manufactured, are convenient to use, and overcome the disadvantages of previous similar undergarments. In addition, they space the trousers from the knees and thighs.

According to the provisions of the patent statutes, I have explained the principle and construction of my invention and have illustrated and described what I now consider to represent its best embodiment. However, I desire to have it understood that, within the scope of the appended claims, the invention may be practiced otherwise than as specifically illustrated and described.

I claim:

1. An improved undergarment having tubular leg portions adapted to reach just below the knees of the wearer, a circumferential hem of relatively inelastic material in the lower extremity of each leg portion, and an elastic tape disposed within the circumference of each hem and having its ends detachably secured at circumferentially spaced points in the sides of the hem, the elastic tape being adapted to rest directly against the front of the wearer's leg and to draw the back of the hem against the back of the wearer's leg and to leave the front of the hem and adjoining undergarment leg portion loosely disposed in front of the wearer's knee.

2. An improved undergarment having tubular leg portions adapted to reach just below the knees of the wearer, a circumferential hem of relatively inelastic material in the lower extremity of each leg portion and provided with buttonholes in its sides, and an elastic tape disposed within the circumference of the hem and having its ends provided with buttons for engaging the buttonholes, the elastic tape being adapted to directly engage the front of the wearer's leg and to draw the back of the hem against the back of the wearer's leg and to leave the front of the hem and adjoining undergarment leg portion loosely disposed in front of the wearer's knee.

3. An improved undergarment having tubular

leg portions adapted to reach just below the knees of the wearer, a circumferential hem of relatively inelastic material in the lower extremity of each leg portion, an elastic tape disposed within the circumference of the hem and having its ends detachably secured at circumferentially spaced points in the sides of the hem, the elastic tape being adapted to rest directly against the front of the wearer's leg and to draw the back of the hem against the back of the wearer's leg and to leave the front of the hem and adjoining undergarment leg portion loosely disposed in front of the wearer's knee, and a catch connected to the elastic tape and extending downward to engage a sock on the wearer's leg.

4. An improved undergarment having leg portions adapted to reach just below the knees of the wearer, a circumferential hem of relatively inelastic material in the lower extremity of each leg portion and provided with circumferentially spaced buttonholes in its sides, an elastic tape disposed within the circumference of the hem and having its ends provided with buttons for engaging the buttonholes, the elastic tape being adapted to rest directly against the front of the wearer's leg and to draw the back and sides of the hem against the back and sides of the wearer's leg and to leave the front of the undergarment leg portion loosely disposed in front of the wearer's knee, and a catch connected to each end of the elastic tape and extending downward to engage and support a sock on the wearer's leg.

5. An improved undergarment having tubular leg portions adapted to reach just below the knees of the wearer, a circumferential hem of relatively inelastic material in the lower extremity of each leg portion, an elastic tape disposed within the circumference of the hem, means for detachably connecting the ends of the tape to the sides of the hem at a plurality of circumferentially spaced points to accommodate legs of different sizes, the elastic tape being adapted to directly engage the front of the wearer's leg and to draw the back of the hem against the back of the wearer's leg and to leave the front of the hem and adjoining undergarment leg portion loosely disposed in front of the wearer's knee.

6. An improved undergarment having tubular leg portions adapted to reach just below the knees of the wearer, a circumferential hem in the lower extremity of each leg portion, and a tape disposed within the circumference of each hem and having its ends detachably secured at circumferentially spaced points in the sides of the hem, the tape being adapted to rest directly against the front of the wearer's leg and to draw the back of the hem against the back of the wearer's leg and to leave the front of the hem and adjoining undergarment leg portion loosely disposed in front of the wearer's knee.
